UNITED STATES PATENT OFFICE.

BENONA S. GLEASON, OF KALAMAZOO, MICHIGAN.

IMPROVEMENT IN FORMING AND DOUBLE-SEAMING STOVE-BOILERS.

Specification forming part of Letters Patent No. 44,417, dated September 27, 1864.

To all whom it may concern:

Be it known that I, BENONA S. GLEASON, of Kalamazoo, county of Kalamazoo, and State of Michigan, have invented a new and useful Improvement on a Machine for Forming and Double-Seaming Stove-Boilers; and I do hereby declare that the following is a full, clear, and exact description of the construction and operation of the same, reference being had to the annexed drawings, making a part of this specification, in which—

Figure 1 is a view of the machine in sections, *a b c*. Fig. 2 is a view of the machine altogether. Fig. 3 is a side view with the semicircular section *a* in Fig. 1 elevated; *d d*, the buttons, *e* the screw, *f* the key, *g* the opening, and *h* the hinge.

The nature of my invention consists in a hinge, *h*, connecting the semicircular section *a* with section *b*, which admits it being elevated, so that it can be dropped easily and quick-

ly to the bottom of the boiler, and by pressing it down to its proper place quickly and easily forms the boiler ready for double-seaming. I then use the screw *e* to spread sections *b c*, so as to admit the key *f* in the opening *g*. I then turn the buttons *d d d* over them, to keep them in their places. I also turn the buttons *d d d* over the hinge *h* while using. There are two keys and two openings in Fig. 3, but only one represented in the drawings.

Having described my invention, what I claim, and desire to secure by Letters Patent, is—

The hinging the semicircular section *a* to the sides of the central section, *b*, in combination with the screw *e* and movable section *c* and key *f*, as and for the purposes set forth.

BENONA S. GLEASON.
